COMBINATION DISPLAY AND MERCHANDISING STAND

Martin Umanoff, Huntington, N.Y., assignor, by mesne assignments, to R. A. MacPlum Industries, Inc., a corporation of New Jersey

Filed June 2, 1960, Ser. No. 60,829

Term of patent 14 years

(Cl. D80—10)

FIG. 1 is a top plan view of a combination display and merchandising stand embodying my new design;

FIG. 2 is a front elevational view thereof on a reduced scale, the rear of the bow being substantially plain; and

FIG. 3 is a side elevational view thereof as shown in FIG. 2.

I claim:

The ornamental design for a combination display and merchandising stand, substantially as shown and described.
